UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

DRAFT RIGGING.

Application filed July 21, 1924. Serial No. 727,375.

To all whom it may concern:

Be it known that I, DONALD S. BARROWS, a citizen of the United States, residing at Rochester, in the county of Monroe and

5 State of New York, have invented certain new and useful Improvements in Draft Rigging; and I do hereby declare the following to be a full, clear, and exact description of the invention, such as will enable 10 others skilled in the art to which it appertains to make and use the same.

The invention relates to draft rigging for railway cars and more particularly to the means for operatively connecting the parts 15 of a draft rigging to the car underframe.

To this end, the principal object of the invention, generally considered, is to provide a plurality of cheek plates or stop castings preferably connected to the outer faces of 20 the center or draft sills of a railway car and comprising front stop members and rear stop members, both sets of stop members being slotted so as to receive transversely extending keys by which the loads imposed 25 on the draft mechanism due to buffing and draft movements of the coupler are transmitted to the sills in alinement therewith.

Another object of the invention is to provide in the construction stated, a mechanism 30 adapted for use under modern service conditions and to so arrange the various stop members that the loads imposed thereon by the transversely extending key or keys do not subject the stop castings to alternate compression and tension loads as is at 35 present the case.

Still another object of the invention is to provide in a three key draft rigging separate stop members for the rear key, the stop 40 members being preferably continued in rear of the key so as to enable the same to be connected to the sills by rivets common to the bolster center filler.

To these and other ends, the invention 45 comprises the various elements and combinations of elements hereinafter set forth.

In the drawings:

Figure 1 is a view partly in plan and partly in longitudinal section of the center 50 framing of a car having the invention applied thereto.

Figure 2 is a top plan view of one of the independent rear stop castings.

Figure 3 is a side elevation of the construction shown in Figure 2.

Figure 4 is a top plan view of one of the front stop castings.

Figure 5 is a side elevation of the construction shown in Figure 4.

Figures 6 and 7 are cross-sectional views 60 taken respectively on lines 6—6 and 7—7 of Figure 5, the direction of view being indicated by the arrows adjacent the ends of said section lines.

Throughout the specification and drawings like parts are designated by like reference characters.

Referring now to the drawings in detail, the numeral 1 designates the center or draft sills of a car which may be of any desired 70 construction and which are provided with a plurality of slots therein, the slots 2 and 3 registering with the slots 4 and 5, respectively, in the front stop members or cheek plates 6. In rear of the slot 3 the center or 75 draft sills are provided with a slot 7, the said slot 7 being adapted to register with the slots 8 of the rear stop members or cheek plates 9. Each of the cheek plates is preferably provided with bosses or inwardly projecting flanges 10, 11 and 12 surrounding the slots 4, 5 and 8, respectively, the said bosses projecting inwardly from the webs 13 of the said cheek plates. On their outer 80 faces the cheek plates are also provided with flanges or bosses surrounding the slots and extending outwardly from the webs 13. These outwardly projecting flanges are designated by the common reference character 14 and the flanges 14, together with the corresponding inwardly projecting flange, give 85 an extended wearing surface for the keys hereinafter described and formed at the limits of the respective slots in the bearing surfaces for engaging the side edges of the said 90 keys. The outwardly projecting flanges 14 are preferably reinforced on the cheek plates 6 by means of the longitudinally extending ribs 15, 16, 17 and 18 and the diagonal rib 19, while on the cheek plate 9 the flange 14 is reinforced at its opposite ends by diagonal flanges 20 and a longitudinal flange 21.

It will of course be understood that the cheek plates are provided with suitable rivet receiving apertures to provide means for 105 connecting the same to the draft sills. The web 13 of the front cheek plate 6 extends rearwardly of the slot 5 to provide an adequate riveting area in the rear of said slot so that buffing forces transmitted by the 110

key to the end wall of the said slot 5 will be transmitted to the center sill without subjecting the portion of said plate forward of said slot to tension stresses. Likewise, 5 the web 13 of the rear cheek plate 9 extends a considerable distance in rear of the slot 8 of the said plate and provides adequate riveting area so that loads imposed upon the rear walls of the slots 8 will be transmitted 10 to the sills without subjecting the remaining portions of the said cheek plates or stop members 9 to tension stresses. It might be pointed out that in car construction where the distance forward of the bolster dia- 15 phragm is sufficient, the rearwardly extending portions of the cheek plates 9 are conveniently connected to the bolster center filler by common rivets, thus utilizing these rivets and disposing the strains thereon so 20 that the rivets are in double shear under compressive loads.

Cooperating with the cheek plates hereinbefore described, is a coupler 22, a front follower 23, a rear follower 24, and a cushioning mechanism or unit 25 diagrammatically illustrated by dot and dash lines. To operatively connect the coupler to the rear follower 24 there is provided a pair of horizontally disposed link or yoke members 26, 30 the said members each preferably formed from a bar of forged steel and each being provided with slots 27, 28 and 29 which are adapted to register with the slots 4, 5 and 8 of the cheek plates. The follower 35 blocks 23 and 24 are slotted, as at 30 and 31, for the reception of transversely extending keys 32, the said keys each being adapted to extend through the follower slots, the corresponding slots in the links, and 40 through the slots in the cheek plates. The coupler is also slotted to receive the transversely extending coupler key 33 which in turn extends through the cheek plates 4, the link slots 27 and the coupler slot. The 45 links 26 are preferably provided at opposite ends with extended bearing surfaces 34 to prevent wear upon the links or keys under draft.

The operation of the device is evident 50 from the foregoing description.

Some of the advantages of the construction hereinbefore described may be briefly pointed out. It has been found in the ordinary three key construction that despite numerous attempts made to strengthen the continuous cheek plates, breakage has not been avoided and it has been discovered by applicant that the breakage of the cheek plates is due not to faulty material but to 55 fatigue of metal which is caused by continuously subjecting the single cheek plates to tension and compression stresses. Applicant has, by the construction hereinbefore described, overcome the defect in the prior cheek plates by providing in rear of each

follower key slot an extended web, the said webs being sufficient in area to accommodate an adequate number of rivets so that the buffing shocks are transmitted to the individual cheek plates as compression strains 70 only. It will be observed that in the particular embodiment of the invention here illustrated, that there is provided on the front cheek plate in rear of the front follower key slot six rivets and a like number 75 of rivets is provided on the rear cheek plates in rear of the rear follower key slot, and since under buffing forces both front and rear keys occupy the rear ends of their respective slots it will be seen that there is provided to withstand buffing shocks a combined shear value of twenty-four rivets which is actually in excess of the compression value of the sills. Since draft shocks are much less severe than buffing shocks 85 there is no occasion to provide on the rear cheek plates a like reinforcement forward of the forward end of the key slot therein but there is provided in the front cheek plates a similar number of rivets, that is 90 six on each cheek plate, which will adequately resist draft loads imposed on the front follower key.

It will therefore be evident that applicant, by his design of individual cheek plates, has 95 provided a draft rigging pocket and stop members suitable for use in connection with modern service conditions and has avoided the defects which have heretofore rendered this type of draft rigging unsuitable for use 100 under modern service conditions.

I claim:

1. In a draft rigging, the combination with a coupler, of slotted front and rear follower blocks, slotted sills, slotted cheek plates connected to said sills, a plurality of keys adapted to extend respectively through said coupler and each follower block, the ends of said keys being received within the slots in said sills and cheek plates, said cheek plates comprising a forward pair adapted to cooperate with the coupler and front follower keys and a rearward pair adapted to 105 cooperate with said rear follower key, and means for reinforcing each of said cheek plates in rear of said follower key slots, said means including a web, a plurality of ribs outstanding therefrom, one of said ribs on each cheek plate extending in alignment with the respective slot therein. 110

2. In a draft rigging, the combination with a coupler, of slotted front and rear follower blocks, slotted sills, slotted cheek plates connected to said sills, a plurality of keys adapted to extend respectively through said coupler and each follower block, the ends of said keys being received within the slots in said sills and cheek plates, said cheek plates comprising a forward pair adapted to 115 cooperate with the coupler and front fol- 120

- lower keys and a rearward pair adapted to cooperate with said rear follower key, and means for reinforcing each of said cheek plates in rear of said follower key slots, said means including a web having a plurality of rivet receiving openings therein, a plurality of ribs outstanding therefrom, one of said ribs on each cheek plate extending in alignment with the respective slot therein.
- 10 3. In a draft rigging, the combination with a coupler, of slotted front and rear follower blocks, slotted sills, slotted cheek plates connected to said sills, a plurality of keys adapted to extend respectively through said coupler and each follower block, the ends of said keys being received within the slots in said sills and cheek plates, said cheek plates comprising a forward pair adapted to cooperate with the coupler and front follower keys and a rearward pair adapted to cooperate with said rear follower key, said cheek plates having outstanding ribs defining the marginal edges of said slots, and means for reinforcing each of said cheek plates in rear of said follower key slots, said means including a web extending rearwardly of the said key slot a distance substantially equal to the length of said slot.
- 15 4. In a draft rigging involving a slotted coupler, slotted front and rear follower blocks, slotted sills, slotted links and keys for operatively connecting said blocks, links and coupler, the combination with cheek plates connected to the sills and adapted to cooperate with the key passing through the rear follower, said 35 cheek plates terminating short of the front follower key slots and having a web extending rearwardly of the slot therein, and means for reciprocating said web comprising a plurality of ribs diverging rearwardly from 40 the adjacent end of said slot.
- 20 5. In a draft rigging involving a slotted coupler, slotted front and rear follower blocks, slotted sills, and keys for operatively connecting said blocks to said sills, the combination with a member positioned in rear of said rear follower and bridging the space between said sills, of cheek plates positioned on the outer faces of said sills, said cheek plates being provided with a slot adapted to 45 register with the slots in the sills for the rear follower key, and means for operatively connecting said bridge member and cheek plates, said means comprising a plurality of rivets extending through each cheek plate, 50 the adjacent sills and the adjacent portion of said bridge member.
- 25 55
- 30 4. In a draft rigging involving a slotted coupler, slotted front and rear follower

In testimony whereof I affix my signature.

DONALD S. BARROWS.
